No. 769,919.

PATENTED SEPT. 13, 1904.

A. L. REID & L. WILSON.

TOY GUN.

APPLICATION FILED JUNE 22, 1903.

NO MODEL.

UNITED STATES PATENT OFFICE.

ALAN L. REID AND LULOFF WILSON, OF CHICAGO, ILLINOIS, ASSIGNEES,
BY MESNE ASSIGNMENTS, TO SAID WILSON.

TOY GUN.

SPECIFICATION forming part of Letters Patent No. 769,919, dated September 13, 1904.

Application filed June 22, 1903. Serial No. 162,462. (No model.)

To all whom it may concern:

Be it known that we, ALAN L. REID and LULOFF WILSON, of Chicago, in the county of Cook and State of Illinois, have invented certain new and useful Improvements in Toy Guns; and we hereby declare that the following is a full, clear, and exact description thereof, reference being had to the accompanying drawings, which form part of this specification.

Our invention relates to toy guns, and has particular reference to toy guns adapted to explode detonating caps.

The primary object of our invention is to provide a toy gun which will be safe in operation, simple in construction, and adapted to be cheaply manufactured.

A further object of our invention is to produce a firing mechanism for toy cap-guns which will have an advantageous action, whereby the caps may be inserted without the danger of a premature explosion and whereby when the mechanism is properly operated a quick positive release of the spring-actuated firing-plunger is effected, enabling said plunger to deliver a sharp free blow upon the cap to be exploded.

With a view to attaining these and other objects, which will become apparent from the following description, our invention consists in certain features of construction and arrangement, which will be hereinafter more fully described, and specified in the claims.

In the drawings, wherein we have illustrated our invention as embodied in a toy cap-exploding cannon, Figure 1 is a section taken in central longitudinal vertical plane illustrating in full lines the position of the parts in the first firing position before the operating-handle is retracted to withdraw the firing-plunger and place the operating-spring under tension and in dotted lines illustrating the position assumed when the operating-handle has been moved to retract the plunger and the connecting-pawl is about to be actuated to release the firing mechanism from the operating-handle. Fig. 2 is a similar view illustrating in full lines the position of the parts

assumed when the operating-handle has completed its full firing sweep, the firing mechanism having been released by the connecting-pawl and returned to initial position, and in dotted lines showing the parts in reloading position. Fig. 3 is a rear elevation of the device. Fig. 4 is a sectional detail taken on line 4-4 of Fig. 1.

Throughout the drawings like numerals of reference refer to like parts.

Referring now to the construction illustrated, 5 indicates a base-block, which may be of wood or other preferred material.

6 indicates a standard or frame of suitable configuration, preferably formed of sheet metal bent to inverted-U form and provided with suitable perforated feet 7, whereby it is secured to the block 5, as by means of screws 8.

Mounted upon the transverse portion of the standard 6 is a metallic barrel 9, preferably formed of sheet metal properly contorted. If this method of manufacture is followed, the barrel will be split at some point, preferably along the under side thereof, as indicated in Fig. 4 at 9'.

10 indicates a cap abutment or anvil arranged at a suitable point within the barrel 9. The anvil 10 is shaped to generally fit within the barrel 9, but is cut out in portions, as indicated at 11, to permit the passage of gas and air therethrough within the barrel. The anvil 10 is provided with suitable lugs 12, projecting from its periphery and engaging in apertures formed to receive the same in the barrel 9. Preferably one of these lugs 12 is disposed to engage the barrel at the top thereof, while other lugs are arranged to engage apertures in the barrel on opposite sides of the slit 9', or, in other words, to engage the opposite edges of the bent barrel. By this means the meeting edges of the barrel are prevented from separating or spreading under the strain occasioned by the explosion of heavy caps.

13 indicates a slot formed in the gun-barrel at any suitable point in rear of the cap-anvil 10.

14 indicates a slot of suitable width extend-

ing longitudinally along the under side of the barrel 9 at the rear end thereof to permit the entrance of a member of the firing mechanism.

The firing mechanism constituting a part of our invention comprises generally an operating-lever mounted for rotation about an axis, a vibrating arm coaxially arranged relative to said operating-lever, a releasable pawl connection between the operating-lever and the vibrating arm, a spring for normally holding the vibrating arm at its forward limit of movement, a firing-plunger, and a connection between said plunger and the vibrating arm.

15 Referring now to the specific embodiment illustrated in the drawings, 15 indicates a transverse shaft mounted in the frame 6 below the opening 14 in the cannon-barrel.

16 indicates a vibrating arm mounted thereon for oscillation and having its upper end extending through the slot 14 in the cannon-barrel into the interior; 17, a plunger-head, preferably of metal, arranged within the gun-barrel and adapted to slide therein, and 18 is 25 a plunger-rod, at one end secured to said plunger-head and at its other end pivotally connected with the extremity of the vibrating arm 16.

20 indicates a spring coiled around the shaft 30 15, at one end finding abutment against a fixed portion of the device, such as the base-block 5, and, at its other end hooked around the vibrating arm 16, so that said spring constantly tends to hold the vibrating arm at its 35 forward limit of movement. It will be understood that the parts are so arranged that the forward movement of the vibrating arm is stopped by the contact of plunger-head 17 with the cap-anvil 10.

40 21 indicates an operating-lever of suitable configuration pivotally mounted upon the shaft 15 for oscillation thereon. At its lower end the lever 21 carries a connecting-pawl 22 pivoted thereto. The pawl 22 is provided 45 with an upturned nose 22^a on the forward side of the pivot and a relatively heavy releasing-arm 22^b extending on the other side of the pivot. The arrangement of the parts is such that the weight of the arm 22^b constantly tends to elevate the nose 22^a, and the parts are so arranged that when the operating-lever 21 is in vertical position said nose 22^a engages a notch shoulder 16^a, formed in the vibrating arm 16 in front of the shaft 15. 55 The arm 22^b is of such length as that when the arm 21 is oscillated with the nose 22^a of the connecting-pawl in engagement with the shoulder 16^a some fixed portion of the framework will intercept the path of the releasing-arm of the pawl. In the present illustration 60 23 indicates an adjustable striking-piece in the form of a screw projecting upward through the base 5 and arranged to be struck by the arm 22^b of the connecting-pawl in its 65 movement as aforesaid.

24 indicates a sleeve surrounding the shaft 15 and arranged to hold the operating-lever 21 in proper lateral relation to the vibrating arm 16.

In Fig. 1 are indicated in their proper positions a cap to be exploded and a cork adapted to be projected by the gun when a cap is exploded therein.

The use and operation of our invention will be as follows: Assuming that the parts are 75 in the position indicated in full lines in Fig. 1—that is to say, with the nose 22^a of the connecting-pawl engaging the shoulder 16^a of the vibrating arm 16 and the explosive cap in position to contact with its anvil 10—movement of the operating-lever 21 rearwardly 80 operates through the pawl connection established by said lever and the vibrating arm 16 to move the said arm rearwardly coincidentally with the operating-lever to the position shown in dotted lines in Fig. 1, thereby retracting with it the firing-plunger. During this initial movement of the connected parts the pawl 22, whose nose 22^a engages shoulder 16^a of the vibrating arm, moves in fixed relation to the operating-lever, so that its extended releasing end 22^b describes an arc which if continued would include the striker member 23. When the extremity of releasing-arm 22^b comes into contact with said 95 striker member 23, however, continued movement of the operating-handle causes the central pivoted portion of the pawl to be depressed relative to the extremity of the arm 22^b, engaging said striker member, thereby 100 throwing the nose 22^a out of engagement with the shoulder 16^a of the vibrating arm. The said arm being thus disconnected from the operating-handle is free to return to initial 105 position under tension of its spring 20, causing the plunger-head to strike the cap against its anvil 10 with a sharp free blow to cause the explosion of the cap. A slightly further movement of the operating-lever 21 brings the parts into the condition illustrated in full 110 lines in Fig. 2, the connecting gravity-pawl 22 being swung to almost vertical position by the weight of its arm 22^b, so that it contacts at two points with the vibrating arm 16 upon the same side of its pivotal axis on the shaft 115 15. Consequently further movement of the operating-lever 21 to the position illustrated in dotted lines in Fig. 2 serves to move the vibrating arm 16 against the tension of its spring to the dotted-line position shown in said figure. The parts are so proportioned that sufficient movement is permitted of the plunger by the loading action to cause the plunger-head 17 to clear the cap-aperture 13, so that a fresh cap may be inserted therethrough. 120 If now the pressure upon the lever 21 be relaxed, the parts will return to the position illustrated in Fig. 2, the plunger-head pushing the cap forward in the barrel until it contacts with its anvil 10, as heretofore described. 125 130

It will be apparent that during this latter operation of loading there is no possibility of a premature explosion of the cap, as the vibrating arm 16 and plunger 17 are fully under 5 the control of the operator.

If desired, the gun may be employed to shoot a cork or other projectile a short distance, the cork being inserted in the mouth of the barrel 13, as illustrated in Fig. 1, so 10 that the expansion of the gases escaping through the apertures 11 in the anvil 10 when the cap is exploded serves to shoot the cork from the gun, as will be well understood.

While we have herein described our invention as applied to a toy gun of the cannon type, we do not desire to be understood as limiting ourselves to its embodiment in this particular form, as it is apparent that many slight changes and modifications might be 20 made in the specific construction of the device without departing from the spirit and scope of our invention. It will also be obvious that while we have described our invention as applied to a gun adapted to explode the caps the firing mechanism thereof might well be applied to spring or air guns, the plunger 17 being then employed to expel the projectile by direct impact or by the compression of air in the rear of said projectile 25 30 in a manner that will be well understood.

Having thus described our invention, what we claim, and desire to secure by Letters Patent of the United States, is—

1. In a toy gun, the combination with a frame, of a barrel mounted thereon, firing mechanism associated with the barrel comprising a vibrating arm mounted in the frame for oscillation, a spring associated with said vibrating arm for normally holding it at its forward 35 40 limit of movement, an operating-lever associated with said vibrating arm for coaxial oscillation, a pawl carried by said operating-lever arranged to operatively engage the vibrating arm to move the same coincidentally 45 with the operating-lever, and a striker member arranged in the path of the pawl, said striker member being adjustable toward and from the axis of oscillation of the vibrating arm to break its connection of said pawl with 50 said vibrating arm sooner or later during the movement of the operating-lever.

2. In a toy gun, the combination with a supporting-frame, of a barrel mounted thereon, a cap-anvil in the barrel, a cap-aperture in 55 rear of said anvil, a spring-plunger mounted for reciprocation in said barrel in rear of the

cap-anvil, a vibrating arm mounted in the frame for oscillation, having its free extremity connected with the firing-plunger, an operating-lever mounted adjacent said vibrating arm for oscillation coaxially therewith, a pawl carried by said operating-lever arranged to constantly tend to make connection with the vibrating arm, and means arranged in the path of movement of the pawl to release said pawl 60 from engagement with the vibrating arm, the parts being so arranged that during a single continuous movement of the operating-lever the pawl establishes releasable connection between the operating-lever and the vibrating 65 arm, to move said arm rearwardly coincidentally with the operating-lever, is moved to break said connection by contact with the striker-member, and subsequently again connects the operating-lever with the vibrating 70 arm for coincident movement.

3. In a toy gun, a frame, a barrel, firing mechanism associated with the barrel comprising a vibrating arm mounted for oscillation in the frame, an operating-lever mounted coaxially with said vibrating arm, a connecting-pawl mounted relative to said axis in fixed relation to the operating-lever, and arranged to establish connection between said lever and the vibrating arm in two different 80 85 positions of movement of the operating-lever, and means arranged for coaction with said pawl to break the first connection with the vibrating arm, and permit the subsequent establishment of the second connection therewith.

4. In a toy gun, the combination with a frame, and a barrel mounted thereon, of firing mechanism comprising a shaft 15, a vibrating arm 16, having a notch 16^a, mounted 90 95 for free oscillation upon the shaft 15, a spring arranged to normally hold said arm at its forward limit of movement, an operating-lever 21, mounted for oscillation on the shaft 15, and extending on both sides thereof, a pawl 100 105 22 having a nose 22^a and a relatively heavy releasing-arm 22^b, mounted on said lever 21, and a striker member arranged in the path of movement of the releasing-arm 22^b.

In testimony that we claim the foregoing as 105 our own we affix our signatures in presence of two witnesses.

ALAN L. REID.
LULOFF WILSON.
